STRAINER

Myron J. Zimmer, Chicago, Ill., assignor to
 Edward Katzinger Company, Chicago, Ill., a
 corporation of Illinois

Application January 11, 1934, Serial No. 706,233

4 Claims. (Cl. 210—161)

This invention relates to strainers and has for its object the permanent securing of the strainer handle to the strainer frame in such manner that the frame is reinforced throughout by the handle and handle frame and at the same time securing the wire gauze bowl to the strainer frame in such manner that the frame of the handle assists in securing the gauze in position and the gauze will be permanently and fixedly secured to the frame.

10 With the above and other objects in view, as will be apparent, this invention consists in the construction, combination and arrangement of parts, all as hereinafter more fully described, claimed and illustrated in the accompanying drawing, wherein:—

Fig. 1 is a plan view of a strainer constructed in accordance with the present invention:

Fig. 2 is a side elevation thereof: and

Fig. 3 is a transverse fragmentary section 20 through the strainer frame being taken along line 3—3 of Fig. 1 to illustrate the mounting of the handle frame and the cooperation between the strainer frame and the gauze.

Heretofore, it has been usual and customary to 25 construct a strainer with a relatively wide metal strainer frame. The gauze of the strainer is seamed to the lower edge of this frame while the upper edge of the frame is bent outwardly, downwardly and inwardly to create a bead which finishes off the upper edge of the frame. It has 30 been customary to secure the handle to the strainer frame by creating a wire handle frame which embraces and bears against the outer surface of the strainer frame between its edges. The wire 35 handle frame is provided with a protruding shank upon which the handle may be secured. It is to be noted that there is no cooperation in this prior type of strainer between the handle frame and the seam whereby the gauze of the strainer bowl 40 is attached to the strainer frame and that the handle frame performs no part or function in reinforcing and bracing the strainer frame. Furthermore, the handle frame is entirely exposed and may be, and frequently is, intentionally or 45 unintentionally removed from the strainer frame.

The present invention has in view an entire arrangement of the strainer frame and its coaction with the gauze of the strainer bowl and the handle frame whereby the gauze will be so permanently and securely fastened to the strainer frame that the possibility of disengagement is eliminated and the handle frame is entirely engaged and covered by the strainer frame. In this manner the handle frame not only is concealed 50 and not susceptible of removal from the strainer

frame, but also helps to reinforce the strainer frame and to assist in maintaining the permanent joint or seam between the strainer frame and the gauze of the strainer bowl.

Reference being had more particularly to the drawing, 10 designates the wire gauze bowl of a strainer which may partake of any suitable shape and size in the finished product, and 11 indicates the strainer frame having an inwardly extending flange 12 at its upper edge and a similar flange 13 at its lower edge.

A wire 14, here shown as round but which may be of any suitable shape, is bent to create a pair of outstanding arms 15 whereby one side of the strainer may be supported upon the lip of a 15 coacting vessel and a loop or ring 16 which constitutes the handle frame. A handle 17 is formed from the frame 16 and is diametrically opposed to the arms 15. It is to be understood that the formation of the wire 14 into the elements aforementioned does not necessarily require that the wire constitute a single unitary piece which is formed into the handle frame 16, the arms 15 and handle 17. This wire may be of one or more pieces as indicated by the joints 18 in the drawing. In the 20 illustrated construction one section of wire 14 forms half of the ring or handle frame 16 and carries the outstanding arms 15, while the opposite or coacting section of wire 14 forms the opposite side or half of the ring or handle frame 16 30 and carries the protruding handle 17.

The wire 14 forming the ring or handle frame 16, either in one or two pieces, is placed within the strainer frame 11 to rest against the flange 13 at the lower edge thereof with the arms 15 35 and the handle 17 projecting through the cut away portions 19 in the frame 11. The flange 13 is then bent inwardly and upwardly to closely and snugly embrace and engage the frame 16.

The bowl 10 of the strainer is then placed with 40 the frame 11 and the edge of the wire gauze forming the strainer bowl is then bent outwardly over the wire 14 and the edge of the lower flange 13 of the frame 11 after which the upper flange 12 of said frame is bent inwardly and downwardly so that the edge thereof bears upon the gauze of the strainer bowl 10 and engages it between the edge of the flange 12 and the body of the wire 14. The edge portion 20 of the strainer bowl thereby becomes coiled or bent within the 50 flange 12 and is entirely encased thereby.

From the foregoing it is manifest that the outer surface of the strainer frame 11 is uninterrupted and merges with the flanges 12 and 13. Upon the interior of the strainer the flanges 12 55

and 13 create two beads, the former a bead which contains the edge portion 20 of the gauze of the strainer bowl 10 and engages the gauze of the strainer bowl between its edge and the wire 14, 5 and the latter a bead in which is contained the wire 14, of the handle frame 16. Manifestly, therefore, the strainer bowl 10 is permanently and rigidly secured to the frame 11 against displacement or disengagement while the wire 14 of 10 the handle frame 16 is similarly secured to the handle frame to assist in maintaining the gauze of the bowl 10 in engagement with the frame 11, as well as reinforce the latter.

In this manner a strainer is constructed having great durability and strength and at the same time being possessed of an increased straining area.

What is claimed is:

1. A strainer comprising a frame, a reinforcing member, said frame having its lower edge bent into engagement with and encircling substantially a major portion of the surface of said reinforcing member, and a strainer bowl having its edge portion engaging only the upper and 25 inner portion of the surface of the reinforcing member and said frame having its upper edge bent inwardly and downwardly into engagement with a part of the edge portion of the strainer bowl to maintain the same in engagement with 30 the reinforcing member aforesaid.

2. A strainer comprising a frame, a reinforcing member, said frame having its lower edge bent inwardly to engage said reinforcing member, and

a strainer bowl having its edge portion bent outwardly to bear on said reinforcing member, and bent to create a peripheral enlargement positioned above said reinforcing member, said frame having its upper edge bent inwardly and downwardly over said enlargement to engage the strainer bowl between it and the said reinforcing member. 5

3. A strainer comprising a frame, a reinforcing member, the lower edge of said frame being bent 10 inwardly and upwardly to engage and partly house said reinforcing member, and a strainer bowl having its edge portion bent outwardly to rest on said reinforcing member, said bowl also having a peripheral enlargement at the extremity of its edge portion positioned above said reinforcing member, the upper edge of said frame being bent inwardly and downwardly over said enlargement. 15

4. A strainer comprising a frame, a reinforcing member, the lower edge of said frame being bent inwardly and upwardly to engage said reinforcing member, and a strainer bowl having its edge portion bent outwardly to bear on said reinforcing member, said bowl also having a peripheral 25 enlargement at the extremity of its edge portion positioned above said reinforcing member, the upper edge of the frame being bent inwardly and downwardly over said enlargement to line 30 grip the strainer bowl between its edge and the said reinforcing member.
